(57) **CLAIM**

The ornamental design for a handheld controller as shown and described.

DESCRIPTION

FIG. 1 is a perspective view of a handheld controller showing my new design;

FIG. 2 is a front view thereof;

FIG. 3 is a rear view thereof;

FIG. 4 is a left side view thereof;

FIG. 5 is a right-side view thereof;

FIG. 6 is a top view thereof;

FIG. 7 is a bottom view thereof; and

FIG. 8 is second perspective view; and,

FIG. 9 is third perspective view showing the handheld controller.

The broken lines shown in the figures are for the purpose of illustrating portions of the handheld controller and form no part of the claimed design.
